UNITED STATES PATENT OFFICE.

EUGENE L. SCHELLENS, OF POINTE CLAIRE, QUEBEC, CANADA, AND JOEL S. COFFIN, JR., OF LISBON, NEW HAMPSHIRE; SAID SCHELLENS ASSIGNOR TO SAID COFFIN, JR.

JOURNAL BOX.

Application filed July 21, 1922. Serial No. 576,618.

To all whom it may concern:

Be it known that we, EUGENE L. SCHELLENS, of Pointe Claire, in the Province of Quebec, Canada, and JOEL S. COFFIN, Jr., of 5 Lisbon, in the county of Grafton and State of New Hampshire, U. S. A., both citizens of the United States, have invented certain new and useful Improvements in Journal Boxes, of which the following is a specification.

This invention relates to journal boxes for railway vehicles and is particularly useful in connection with trucks, such as the locomotive trucks, shown, described and 15 claimed in our copending application, Serial No. 576,616, filed July 21, 1922.

It is one of the primary objects of our invention to provide a self-aligning journal box which will maintain itself in alignment 20 with the axle thus avoiding "running hot", excessive wear on the brasses or other bearing employed, and similar difficulties.

Another object of the invention is the provision of a box which will reduce pedestal jaw wear and which is not affected by 25 lateral wear within wide limits.

The foregoing, together with such other objects as may hereinafter appear, or are incident to our invention, we obtain by 30 means of a construction which we have illustrated in preferred form in the accompanying drawings, wherein:

Fig. 1 is a fragmentary side elevation and 35 partial section of a pedestal and box embodying our invention;

Fig. 2 is a sectional view through the pedestal illustrating the box in side elevation; and

Fig. 3 is a horizontal section through the 40 pedestal illustrating the box in plan view.

On reference to Fig. 1 it will be seen that we have illustrated a portion of a truck frame 7 having a pedestal 8 adapted to receive the journal box A between its jaws 9.

The box A, in general construction, may be 45 of any preferred type. We provide the box, however, with a plurality of curved bearing surfaces, where the box bears on the pedestal parts. In the embodiment shown we employ a curved or arcuate insert 10 in the top of the box and similarly curved inserts 11 at the sides of the box, such inserts being located in the middle vertical plane of the box, the direction of curvature and clearances being such that the box, in a sense, can 50 rock within the pedestal in an amount under all conditions of service sufficient to permit the box to remain in alignment with the axle 12. The mounting of the box in the pedestal is thus somewhat after the nature of a ball 60 and socket joint and has capacity for a universal-like motion.

The practical advantages of our construction will be manifest; and it is especially useful in such constructions where there is 65 a liability of springing of the truck frame or where there are other conditions tending to produce disalignment of the boxes with the axle.

What we claim is:

1. In combination, a journal box for railway vehicles, a part carrying the box and pads secured to the box at the sides thereof having a substantially vertical line contact with the carrying part.

2. In combination, a journal box for railway vehicles, a part carrying the box and pads secured to the box at the sides thereof having a substantially vertical line contact with the carrying part together with a pad 80 secured to the top of the box having a horizontal line contact with the said part in a direction transverse the box.

In testimony whereof, we have hereunto signed our names.

E. L. SCHELLENS.
J. S. COFFIN, JR.
